UNITED STATES PATENT OFFICE.

WILLIAM KEMBLE, OF KINGSTON, NEW YORK.

WINDOW-SHADE HANGER.

1,222,632.

Specification of Letters Patent. Patented Apr. 17, 1917.

Application filed June 8, 1915. Serial No. 32,894.

To all whom it may concern:

Be it known that I, WILLIAM KEMBLE, a citizen of the United States, residing at Kingston, in the county of Ulster and State 5 of New York, have invented a new and useful Window-Shade Hanger; and I do hereby declare the following to be a full, clear, and exact description of the invention, such as will enable others skilled in the art to 10 which it appertains to make and use the same.

This invention relates to an improved window shade hanger, and an object of the invention is to provide a hanger which is 15 adjustable, to fit different widths of window frames.

Another object of the invention is to provide a sectional hanger, the sections of which are adjustably connected, the adjustable connections of two sections including yieldable means, whereby the hanger may be yieldably clamped to the window frame.

In practical fields the details of construction may necessitate alterations, falling 20 within the scope of what is claimed.

The invention comprises further features and combination of parts, as hereinafter set forth, shown in the drawings and claimed.

In the drawings:—
30 Figure 1 is a view in elevation of a portion of a window frame, illustrating the improved adjustable hanger as applied thereto.

Fig. 2 is a plan view of the hanger, showing parts of the window frame in section.

35 Fig. 3 is a sectional view on line 3—3 of Fig. 1.

Fig. 4 is an enlarged detail perspective view of a portion of a hanger, showing the yieldable adjustable connections between two 40 of the sections of said hanger.

Referring to the drawings, 1, 2, and 3 designate the three sections of the hanger. The section 1 has one of its ends provided with a laterally extending ear 4 provided with 45 lugs 5 to engage one side 6 of the window frame 7. The section 3 at one end is provided with a laterally extending ear 8 having lugs 9 to engage or embed in the other side 10 of the window frame 7. The end 50 portion 11 of the section 1 has lugs 12 provided with bent portions 13 extending toward each other and overlying the opposite edge portions of the section 2, to guide the sections 1 and 2 when adjusted relative 55 to each other. The end portion 14 of the section 2 has ears 15 bent toward each other

and overlying the rear face of the section 1, to assist in guiding the sections 1 and 2 in their movements, when being adjusted. Also adjacent the end portion 11 of the section 1 is a projection 16, which is designed to engage or penetrate any one of the series of elongated slots 17 of the section 2, for holding the sections 1 and 2 in their adjusted positions. The several sections of the hanger are constructed preferably of spring sheet metal, and it is to be observed that the bent portions 13 of the lugs 12 are spaced sufficiently from one face of the section 1, in order to permit the end portion 11 of the section 1 to be sprung apart from one face of the section 2, to enable the projection 16 to be withdrawn from any one of the slots 17, so as to permit it to be adjusted into another of the slots 17. There are two 70 brackets 19 and 20 provided, one carried by the section 1, the other by the section 3. These brackets 19 and 20 are angular in plan view and are provided with ears 21 extending toward each other and overlapping said sections 1 and 3, so as to be slidably mounted upon said sections, being held in their adjusted positions upon said sections frictionally. The upper edge portion of each of the brackets 19 and 20 is provided with a lug 80 85 22, which also overlies its adjacent section, thereby constituting means for assisting in guiding said brackets when adjusted. The outwardly extending part of the bracket 20 is provided with an elongated opening 23, to receive the usual pintle (not shown) rectangular in cross section, of the shade roller (not shown). The outwardly extending portion of the bracket 19 is provided with an aperture 24 to receive the cylindrical pintle (not shown) of the other end of the shade roller (not shown). The outwardly extending parts of both brackets 19 and 20 are provided with upwardly extending portions or ears 25, which are provided with slots 26, 100 which may receive the pintles of a shade roller (not shown), or contracted portions (not shown) of a curtain pole (not shown). If a curtain pole is supported by the upwardly extending portions or ears 25, and a shade roller supported in the opening 23 and the aperture 24, it will be seen that said brackets constitute combined shade roller and curtain pole supports.

The end portion 27 of the section 3 has 110 ears 28 bent toward each other and overlying the section 2 of the hanger. The adj-

cent parts of the ears 28 (which guide and hold the sections 2 and 3 relative to each other) are provided with outwardly extending parallel lugs 29, between which, and upon the pin 30, the U-shaped part 31 of the lever 32 is pivoted. Extending transversely of the U-shaped part 31 of said lever and spaced from the pivot pin 30 is a second pivot pin 33. The end portion 34 of the section 2 is provided with ears 35, which also bend toward each other and overlie the section 3 of said hanger, thereby additionally guiding the sections 2 and 3 relative to each other. Rolls or sleeves 36 are disposed adjacent to and between the ears 35 and form integral parts of the end 34 of the section 2. Mounted in said rolls or sleeves is a pin 37, and disposed between said rolls or sleeves is an eye 38 (through which the pin 37 extends) of the link 39, midway of the opposite ends of which a spring or resilient coil 40 is constructed. The eye 41 at the other end of said link 39 receives the pin 33. In applying the hanger to a window frame, the lever is thrown back to a position just the opposite to that shown in Fig. 4, thereby extending the section 3 of the hanger relative to the section 2. Then the sections 1 and 2 are adjusted relative to each other, so that the lugs 5 and 9 will just pass the opposite edges of the window frame, subsequently to which the lever 32 is thrown or moved to the position shown in Fig. 4, and owing to the disposition of the pins 30 and 33 relative to each other, the section 3 of the hanger is drawn toward the section 2, and owing to the spring or resilient coil 40, the lugs 9, as well as the lugs 5 yieldably embed themselves into the opposite sides of the window

frame. It will be observed that when the lever 32 is arranged or disposed as shown in Fig. 4, the pivot pin 33 assumes a position closer to the section 3 of the hanger than the disposition of the pin 30, owing to which arrangement, the link 39 together with the spring coil 40 acts to hold the lever 32 in the position shown in Fig. 4.

The invention having been set forth, what is claimed as new and useful is:—

A window shade fixture comprising a hanger bar having jaws at its opposite ends to engage the opposite edges of a window frame, shade roller brackets mounted upon the bar, said bar consisting of three sections, means to adjustably and positively and rigidly connect the ends of two of the sections, the inner end of one of the end sections having ears bent over the adjacent end of the intermediate section and terminating in an opposed lug, the end of said intermediate section adjacent said section having the ears being provided with ears overlying said end section, a lever pivoted between said lugs, and a wire link having a central resilient coil, one end of said link being pivoted to said lever eccentric or offset from the pivot of the lever, the other end of said link being pivoted between the last named ears, whereby when the lever is thrown toward the link, said jaws will be drawn toward and in engagement with the opposite sides of the window frame.

In testimony whereof I have signed my name to this specification in the presence of two subscribing witnesses.

WILLIAM KEMBLE.
